US00D887431S

(12) **United States Design Patent** (10) **Patent No.:** **US D887,431 S**
(45) **Date of Patent:** **** Jun. 16, 2020**

(54) **DISPLAY SCREEN WITH GRAPHICAL USER INTERFACE**

(71) Applicant: **Genomic Prediction, Inc.**, North Brunswick, NJ (US)

(72) Inventor: **Laurent Christian Asker Melchior Tellier**, New Brunswick, NJ (US)

(73) Assignee: **Genomic Prediction, Inc.**, New Brunswick, NJ (US)

(**) Term: **15 Years**

(21) Appl. No.: **29/653,727**

(22) Filed: **Jun. 18, 2018**

(51) **LOC (12) Cl.** **14-04**

(52) **U.S. Cl.**

USPC **D14/486**

(58) **Field of Classification Search**

USPC D14/485-495

CPC G16H 50/20; G16H 10/60; G16H 50/30;

A61B 5/02; A61B 8/46; G06T 2207/30004

See application file for complete search history.

(57) **CLAIM**

The ornamental design for a display screen with graphical user interface, as shown and described.

DESCRIPTION

The FIGURE is a front view of a display screen with graphical user interface, showing my new design.

The broken lines in the drawing illustrate the display screen and portions of the graphical user interface which form no part of the claimed design.

1 Claim, 1 Drawing Sheet
